METRONOMIC TEMPO INDICATOR

Friedrich Walter Koenigsberger, London, and
Angus MacPhail, Hitchin, England; said Mac-
Phail assignor to said Koenigsberger; said
Koenigsberger now by judicial change of name
Walter Frederick Coningsby

Application May 23, 1945, Serial No. 595,348
In Great Britain June 1, 1944

3 Claims. (Cl. 58—130)

1

This invention relates to metronomic tempo indicators.

The usual tempo indicator, known as a "metronome," consists of an oscillating steel rod worked by a clockwork mechanism and suspended on a pivot with a fixed weight at its lower end and a smaller and movable weight at its upper end, which smaller weight, by being placed nearer to the pivot, increases the oscillations of the rod per unit period.

The hitherto known metronomes suffer from various disadvantages. Thus the position of the smaller weight and consequently the rate of oscillation of the pendulum can be adjusted only while the metronome is stationary. Moreover the clockwork driving mechanism must be wound up periodically, and finally the indicating signals are of a constant intensity.

One object of the invention is to provide a tempo indicator which can operate for long periods without interruption.

Another object of the invention is to provide a tempo indicator, the periodicity of the signals of which is adapted to be varied gradually or momentarily during the normal operation of the device.

Still a further object of the invention is to provide a tempo indicator the intensity of the beats of which is adaptable to the conditions of the music, i. e. the sound level of the instrument or instruments, the character of the music and the environmental background.

Still a further object of the invention is to provide a metronomic tempo indicator which is operated electrically instead of mechanically.

Still a further object of the present invention consists in a metronomic tempo indicator comprising means for producing an audible or visible signal at regular intervals, means for regulating the intensity of said signals during the operation of the device and means by adjusting the tempo of said signals during the normal operation of said device.

Other objects and advantages of the invention will become apparent from the following description and claims.

In the drawings, forming part of this specification:

Fig. 1 is a diagrammatic representation of one embodiment;

Fig. 2 is a detail of Fig. 1; and

Fig. 3 is a diagrammatic representation of a second embodiment.

In said drawings, like parts are indicated by like reference characters.

2

In the embodiment shown in Fig. 1, 1 denotes a synchronous electric motor driven from a mains circuit A, the shaft 2 of which motor drives one cone 4 of a twin cone friction gear 4, 5, through a reduction gear 3.

The transmission ratio of the cone friction gear 4, 5, is varied by a wheel or runner 6 rotatably mounted on a shaft 7 having at its other end a rack 8 engaging a pinion 9 carrying an indicator pointer 10 moving below a transparent calibrated dial 11.

The position of the pointer 10 and thus of the runner 6, is adapted to be altered by a knob 12 (Fig. 2).

15 The cone 5 is mounted on a spindle 13 carrying a finger or cam 14 which, during each revolution of the cone, strikes the leaf 15 of a leaf switch 16, 17, 18, in a mains fed circuit 20 in which is a rectifying circuit comprising a rectifier 21 (for example a dry plate rectifier). The rectified current from rectifier 21 passes through a resistance 22 via points 16, 17 of the leaf switch which are normally in contact, to charge a condenser 23, passing from thence via return lead 24 to the mains.

20 When the cam 14 momentarily depresses the contact 16 into contact with the contact 18 part of the charge of the condenser 23 is transferred to a sound-producing electrical device 25 of any desired known construction, such as a hammer armature, a loud speaker or the like whilst another part of the charge of the condenser 23 is transferred through a rheostat 26 with movable contact 26a and limiting resistance 27, back to the condenser 23.

the leaf switch 16, 17, 18 thereby alternately bringing about the charging and discharging of the condenser 23 and thus causing the sound producing device 25 to emit audible signals of constant periodicity.

As will be seen from the foregoing description, the periodicity of the signals can be varied by moving the runner 6 by turning knob 12, whilst the intensity of the emitted signals can be varied by altering the position of the contact 26a, which may be effected by a knob (not shown) in close proximity to the knob 12 or even coaxial therewith.

The embodiment shown in Fig 3 operates purely electrically and broadly consists of an electronic time base circuit.

Said circuit comprises a transformer T, the primary coil 50 of which is fed with A. C. mains current through a fuse 35 and switch 36. Said transformer T feeds four secondary windings 51, 52, 53, 54. Winding 51 energises the heater of a rectifying tube 55, the anodes of which are fed by the secondary winding 52, producing direct current which is smoothed by a condenser 56.

Winding 53 excites the heater of a gas discharge triode 57 whilst the winding 54 energises the heater of a pentode 58.

Rectified current from rectifier 55 charges a condenser 59 through a resistance 60 and pentode 58 whose cathode 58a and third grid 58c are tied and whose anode 58d and second grid 58b are likewise tied. The anode 58d is connected to a point 65 in the circuit between resistance 60 and a further resistance 61 in series with resistance 60, the two resistances 60 and 61 being shunted across the rectified current supply. A by-pass condenser 62 is further shunted across the resistance 61.

The cathode 58a of the pentode 58 is biased through the voltage drop produced by a resistance 63 and a potentiometer 64, the movable contact of which can be operated by a knob 12 which carries a pointer 10 traversing a calibrated tempo scale 11 illuminated by a pilot lamp 66.

The grid 58e of pentode 58 derives its bias from the negative end of a cathode resistance 67.

The gas discharge triode 57 has its cathode 57a tied to point 65 while the bias to the grid 57b is fed through a resistance 68 and the anode 57c is connected to the primary 70 of a transformer T1 and to the condenser 59. The secondary winding 71 of the transformer T1 actuates a loud speaker or other sounding device 25 the intensity of the signals emitted by which is controlled by a potentiometer 73.

The loudspeaker 25 may obviously be replaced by a lamp or other visual signalling device.

The circuit operates as follows:

On closing the mains switch 36 the primary 50 of transformer T is energised, thereby simultaneously energising the heaters of tubes 55, 57 and 58, tube 55 delivering direct current which charges condenser 59 through the constant current charging pentode 58. When the potential of the condenser 59 reaches the breakdown point of the gas triode 57, the condenser is instantly discharged through the primary 70 of transformer T1, the secondary 71 of which actuates the loudspeaker 25.

From the foregoing description it will be seen that the periodicity of the signals emitted by the loudspeaker or other device 25 can be varied by varying the resistance of the potentiometer 64 by means of knob 12 while the intensity of the

emitted signals can be varied by varying the resistance of the potentiometer 26.

The metronomic tempo indicator of the present invention is not restricted for use in the practice of music, but is particularly suitable for medical treatment, for rehabilitation and for mental or physical gymnastics.

We claim:

1. In a metronomic tempo indicator an electric circuit including an electric motor; an infinitely variable cone friction gear including an intermediate runner; said gear being driven by said electric motor; a switch in said electric circuit; switch closing means driven by said cone friction gear; a sound emitter in said electric circuit actuated by the closing of said switch; rack and pinion means for varying the position of said intermediate runner and thus the transmission ratio of said cone friction gear; a control knob for actuating said pinion; an electromagnetic clutch connecting the pinion and said control knob; said clutch being operated from the same circuits as said motor to be energized simultaneously therewith and a rheostat in said electric circuit for varying the intensity of the sound emitted by said sound emitter.

2. In a metronomic tempo indicator a stationarily mounted electric motor; a first cone having a stationary axis and being driven by said motor; a second cone having a stationary axis; a movable intermediate runner arranged between said cones; said cones and said runner forming part of a cone friction gear; means for varying the position of said runner; a knob; an electromagnetic clutch connecting said knob and said varying means; means for energizing said clutch simultaneously with said motor; a stationary switch operated by said second cone; a stationary contact in said switch; and a sound emitting device connected to said contact.

3. In a metronomic tempo indicator a stationarily mounted electric motor; a first cone having a stationary axis and being driven by said motor; a second cone having a stationary axis; a movable intermediate runner arranged between said cones; said cones and said runner forming part of a cone friction gear; means for varying the position of said runner; a knob; an electromagnetic clutch connecting said knob and said varying means; means for energizing said clutch simultaneously with said motor; a stationary leaf switch including a movable leaf and being operated by said second cone; a stationary contact in said switch adapted to contact periodically said movable leaf; and a sound emitting device connected between said contact and said movable leaf.

FRIEDRICH WALTER KOENIGSBERGER.
ANGUS MACPHAIL.
